UNITED STATES PATENT OFFICE.

ARTHUR C. HOUSE, OF WELDON, NORTH CAROLINA.

SAMPLE HOLDER AND LABEL FOR CLOTH BOARDS OR BOLTS.

Application filed October 23, 1926. Serial No. 143,677.

My invention relates to an improved holder and label applicable to a cloth board, to conveniently retain a removable sample of fabric, and at the same time to provide an end label for the board and bolt, and to the combination of such a sample holder and label with the board and cloth bolt.

The general object is to provide a simple and economical device of this class which 10 may easily be applied to the cloth board and which contains and retains a fabric sample or a folder or other container for the sample in a convenient way for easy removal and replacement.

15 In a preferred form, as here shown, the device consists of a blank of cardboard or similar inexpensive material, folded and otherwise constructed to provide a pocket or enclosure for the sample or sample container, this pocket being located upon one broad face of the cloth board and accessible at an end thereof, and also to provide in some cases an end label overlying the end of the board, and preferably also a flap underlying the opposite broad face of the board to aid in retaining the device in proper position.

20 The characteristics and advantages of the invention are further sufficiently explained 30 in connection with the following detail description of the accompanying drawing, which shows one representative embodiment of the invention. After considering this example, skilled persons will understand 35 that many variations may be made, and I contemplate the employment of any structures that are properly within the scope of the appended claims.

In the drawings:

40 Fig. 1 is a perspective view of a cloth bolt in which the invention is incorporated in one form.

Fig. 2 is a section at 2—2, Fig. 1.

45 Fig. 3 is a perspective view of one end of a cloth board with the sample holder and label applied thereto.

Fig. 4 is a plan view of the blank before folding.

50 Fig. 5 is a perspective view of one suitable sample folder or container.

Fig. 6 is a perspective view of a modified construction.

55 The invention may be combined with or adapted to almost any form of cloth board. The representative form shown consists of a frame including side pieces 1, end pieces 2,

the ends of which preferably overlap the ends of the side pieces and have rounded formations to conform to the rounded edge contour of the side pieces, and usually a central cross piece 3. This frame is covered with sheet material, usually heavy paper or thin cardboard 4, wrapped and secured about the broad sides and rounded edges of the frame.

60 My improved sample holder and label is 65 desirably formed from an integral blank B, Fig. 4, usually of cardboard or similar sheet material, of moderate thickness and stiffness, but readily foldable. The blank includes main pocket flaps 5 and 6, a label portion 7 70 and an under or retaining flap 8. The width of the portions 5, 6 and 8 is usually somewhat less than that of one of the broad sides of the cloth board, and the label portion 7 is dimensioned to substantially exactly cover 75 and conform to the contour of the outer face of the end piece 2, that is, it includes rounded extensions 7^a to conform to the round end contours of the cloth board ends 2. The under or retaining flap 8, desirably, has its 80 corners cut away as at 9.

85 The blank is folded along the lines 10, 11 and 12, as shown in Figs. 2 and 3, and placed upon the cloth board so that the label portion 7 covers the outer face of the cloth board and member 2, the flap 6 lies upon one broad face of the board with its inward end (defined by the fold line 10) overlying the cross piece 3, and the outer flap 5 folded down upon flap 6, while the retaining or under 90 flap 8 lies against the opposite broad face of the board. Any suitable fabric sample R, Fig. 5, which is usually a piece cut from the cloth to be wound upon the board, may be placed between the pocket flaps 5 and 6 95 either before or after the fabric is wound upon the board. The sample may simply be placed between the flaps 5 and 6 without other container or protection; otherwise, it may be placed in an envelope or in a folder 100 F, Fig. 5, and secured therein in any suitable way, or left free if preferred.

105 The fabric is now wound upon the board in the usual way, producing a complete cloth bolt, shown in Fig. 1, with the fabric overlying the pocket flaps 5 and 6, and also overlying the under flap 8 and retaining the sample holder in position, and also retaining the sample or its folder F in position between the pocket flaps 5 and 6 until it is intentionally 110 removed for removal of a piece for presentation to a customer, for example. Otherwise,

the sample or its folder F may be pushed in between the pocket flaps 5 and 6 after the fabric is wound upon the board. Of course, after removal the sample or its folder or container may easily be replaced within the pocket provided by the flaps 5 and 6.

The folder may desirably be provided with means such as the tape or ribbon S for conveniently manipulating it. As shown, this 10 ribbon is secured to one flap of the folder and run through a slot in the other flap so that the act of pulling the free end of the ribbon will close the folder. When the folder is positioned within the holder the tape or ribbon 15 hangs in an accessible position at the end of the cloth bolt and serves as a handle or tab by which the folder may easily be removed.

If any means other than the fabric wound 20 upon the board is not employed to secure the holder in position, tacks 20 may be driven through end portions 7^a of the label section 7 into the end piece 2, which is usually of wood, pulp or other material suitable to receive and hold the tacks.

25 Fig. 6 shows a modified form or arrangement of the holder which, in this instance, consists merely of the connected pieces or flaps 5 and 6, one of which lies upon one face of the board or winder, and is secured by 30 the usual end finishing strip or label 7^b. The mode of use will be understood from the preceding description of Figs. 1 to 5.

I claim:

1. A holder of the character specified, including a strip of sheet material folded to 35 provide three integrally connected folds lying one above the other, the connection between the top fold and the central fold being at one end of the holder and of a character

such that the top fold lies directly on the 40 central fold, the connection between the central and bottom folds being at the opposite end of the holder and in the form of a label 45 spacing the bottom fold from the central fold, the label being of a width such that when the bottom fold is inserted beneath the cloth board, with the top and central folds upon the top thereof, the label will be at the end of the board and will substantially cover the same.

2. A holder of the character specified, including a strip of sheet material folded to 50 provide three integrally connected folds lying one above the other, the connection between the top fold and the central fold being at one end of the holder and of a character 55 such that the top fold lies directly on the central fold, the connection between the central and bottom folds being at the opposite end of the holder and in the form of a label 60 spacing the bottom fold from the central fold, the label being of a width such that when the bottom fold is inserted beneath the cloth board, with the top and central folds upon the top thereof, the label will be at the end of the board and will substantially cover the same, and a sample holding folder between the top and central folds, said folder 65 consisting of two folds integrally connected at one end, and detachably connected at the 70 other by a tape secured to one fold and passing through an opening in the other to enable easy withdrawal of the folder.

Signed at New York city, in the county of 75 New York, and State of New York, this 21st day of October, A. D. 1926.

ARTHUR C. HOUSE.
